UNITED STATES PATENT OFFICE

103,185

DESIGN FOR A DRESS

Tora Coleman, New York, N. Y.

Application December 11, 1936, Serial No. 66,474

Term of patent 3½ years

To all whom it may concern:

Be it known that I, Tora Coleman, a citizen of Latvia and a resident of the Borough of Manhattan, city of New York, county of New York, and State of New York, have invented a new, original, and ornamental Design for a Dress, of which the following is a specification, reference being had to the accompanying drawing, forming part thereof, wherein

my new design.

I claim:
The ornamental design for a dress as shown.

TORA COLEMAN.
